HIS ATTORNEYS

UNITED STATES PATENT OFFICE

HERMAN HANSEN, OF CHICAGO, ILLINOIS

BOX

Application filed August 5, 1931. Serial No. 555,329.

This invention relates to certain novel improvements in boxes, and has for its principal object the provision of an improved construction of this character which will be highly efficient in use and economical in manufacture.

It is an object of this invention to provide an improved box and fasteners therefor.

It is another object of the invention to provide improved fibre box fasteners which are less expensive to manufacture than the fasteners heretofore used, which will be easily manipulated into and out of fastening position, and which will reliably keep the closure elements of the box in closed position under all kinds of service and circumstances.

Another object of the invention resides in providing an improved box including reinforcing elements for the closure flaps.

A further object of the invention resides in arranging the fasteners in such a manner that they may be pivoted and swung into position to move up and down and frictionally engage the ends of the box when it is desired to keep the box opened but unlatched, thus permitting the closure members to be opened and closed and keeping them closed without the use of the latching elements.

Other objects will appear hereinafter.

The invention consists in the novel combination and arrangement of parts to be herein-after described and claimed.

The invention will be best understood by reference to the accompanying drawing showing the preferred form of construction, and in which:

Fig. 1 is a perspective view of the invention;

Fig. 2 is a transverse sectional view of the invention; and

Fig. 3 is a fragmentary sectional view on line 3—3 in Fig. 2.

In the drawing, which illustrates a preferred and practical embodiment of my invention, a box is indicated generally at 10 and includes end flaps 11, closure flaps 12 and 13, and a side wall 14. While I may attach my improved fasteners, indicated generally at 15, directly to the flap 12, I preferably employ a reenforcing strip 16 that overhangs and ex-

tends parallel to the meeting edge 17 of the flap 12 and this strip 16 is secured to the flap 12 by suitable connecting elements such as, for example, rivets 18, the fasteners 15 being pivotally connected to the strip 16, as at 21, so that the fasteners may be pivoted into the dotted line position of Fig. 1 when it is desired to keep the box closed but unlatched, the legs 22 of the fasteners then frictionally engaging the ends of the box and keeping the closure flaps in closed position without the use of the latching elements, as when requiring frequent access to the box to examine files stored therein, while permitting the closure flaps to be readily opened and closed.

My improved fastener includes a leg 19 of resilient material which may well be of metal, and this leg 19 is secured to the portion 20 of the reenforcing strip which overlaps the flap 13 when in closed position, as shown in Fig. 2, by a suitable connecting element, such as rivet 21.

Each of my improved L-shaped fasteners 15 includes a resilient leg 22 that is bent substantially at a rightangle to the portion 19 and this leg 22 is provided with an aperture or female element 23 for the reception of the male fastening element 24 that is mounted upon the side wall 14 of the box.

In use, the portion 20 of the reenforcing strip 16 overlaps a part of the flap 13 thus keeping the two flaps 12 and 13 in alignment while reenforcing the break therebetween. To close the box the flap 13 will first be moved into the position shown and the flap 12 then brought down so that the portion 20 of the strip 16 overlaps a part of the flap 13, a slight downward pressure being exerted upon the fasteners 15 to cause the lips 25 thereof to snap over the male elements 23 which will thus be received in the apertures 23, the box being opened by pulling the legs 22 into the dotted line position of Fig. 2.

While I have illustrated and described the preferred form of construction for carrying my invention into effect, this is capable of variation and modification without departing from the spirit of the invention. I, therefore, do not wish to be limited to the precise details of construction set forth, but desire

to avail myself of such variations and modifications as come within the scope of the appended claims.

Having thus described my invention, what I claim as new and desire to protect by Letters Patent is:

1. A fibre box comprising a body having an open side and closure members therefor, a reenforcing strip on one of said members overlapping a portion of the other member when the same are in closed position, a fastening device comprising a substantially L-shaped strip including a leg pivotally attached to said reenforcing strip and extending over the other of said closure members when in fastened position, a male element on said body, and said strip including a resilient leg provided with an aperture for the detachable reception of said male element, said device being adapted to be pivoted so that said second-named leg may be frictionally engaged with an end of said box and keep said closure members in closed position without the use of said element while permitting

25

said closure members to be readily opened and closed.

2. A box comprising a body having an open side and closure members therefor, one of said closure members having an edge portion overlapping the other of said members along their meeting edges when in closed position, a fastening device comprising a member including right-angularly intersecting legs, one of said legs having an end portion pivotally attached to the said one of said closure members and extending over the other of said closure members when the latter are in closed position, a stationary fastening element on said body the other of said legs being formed for detachable attachment to said element, said fastening device member being adapted to be pivoted so that said second-named leg thereof may be frictionally engaged with an end wall of said body to keep said closure members in closed but unlatched position without the use of said element.

In testimony whereof I affix my signature.

HERMAN HANSEN.
